UNITED STATES PATENT OFFICE.

LEGER J. CASTONGUAY, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

INCANDESCENT-LAMP SOCKET.

986,138.

Specification of Letters Patent. Patented Mar. 7, 1911.

Application filed January 21, 1910. Serial No. 539,226.

To all whom it may concern:

Be it known that I, LEGER J. CASTONGUAY, a citizen of the United States of America, residing in the city of Bridgeport, in the 5 county of Fairfield, in the State of Connecticut, have invented certain new and useful Improvements in Incandescent-Lamp Sockets, of which the following is a specification.

10 One of the main objects of my invention is to so construct a key socket for electric incandescent lamps that the axis of the key handle will always be substantially at right angles to the axis of the lamp socket no matter to what position it may be turned, and a further object is to construct an efficient key socket with double break.

In the accompanying drawings Figure 1 is a vertical section of a socket constructed 20 in accordance with my invention, the lined cap and shell being omitted for the sake of simplicity, and the key being shown in the position in which the circuit is closed; Fig. 2 is a similar sectional view, showing the 25 key turned to the position where the circuit is broken; Fig. 3 is an inner face view of the lower insulating block; Fig. 4 is an inner face view of the upper insulating block with the switch key in the position shown in 30 Fig. 2; Fig. 5 is a perspective view of the switch device.

While my invention may be applied to sockets of a single insulating block type, I prefer to employ the Perkins' double insulating block form of the Perkins Patent No. 35 626,927, and I have so shown it in the accompanying drawing.

The lower insulating block A carries as usual the lamp-receiving terminals S and 40 C, the latter being in electrical connection with a contact plate D in a recess in the inner face of the lower block A. The switch block F is in this case mounted upon a spindle f having bearings in the U-shaped frame 45 F', which in the present case is shown as secured in a suitable recess formed for it in the inner face of the upper block B.

I prefer to provide the lost motion connection between the handle H and the spindle f, and for this purpose the handle H has a stem h¹ which has a bearing in a washer h held in semi-circular recesses of

the adjacent faces of the two blocks A and B, and those adjacent faces of the two blocks may be further recessed to form a direct bearing for the short stem h¹ of the handle H, and also for the hub of the handle. The inner end of this stem is transversely elongated at x to engage with some lost motion the opening in the end of the cam E, Figs. 60 1 and 5.

On the end of the spindle f opposite that which carries the switch block F secure a cam block E. On this cam block E bears a spiral spring P set into the recess in the inner face of the upper block and preferably having a bearing plate p against which the surface of the cam block may make frictional contact. In a recess in the upper block over the switch block F is a spring 65 70 contact plate G in electrical connection with a binding post 12 carried by the upper block. The screw shell S will be in electrical connection with the other binding post 13 which is shown in Fig. 3. 75

In the above described construction of my socket it will be seen that in one position illustrated in Fig. 1, the switch block F makes electrical connection between the spring contact plate G connected to the binding post 12 and the contact plate D connected to the lamp terminal C, and the spiral spring P bearing on the rectangular upper end of the cam block E will tend to retain the parts in that position. When the 80 85 key H is turned from the position shown in Fig. 1 to that shown in Fig. 2, the circuit will be broken with a snap break not only between the switch block F and the spring contact G but also between the switch block F and the contact D, thus giving a double. 90 95 break, and the spring P, by acting upon the cam block E, will maintain the switch block F in the position shown in Fig. 2, until the key is intentionally turned to another position.

With the construction described there will be no tilting of the key such as is common in many types of key sockets, but the key handle will be maintained with its axis always at right angles to the axis of the socket. 100

I claim as my invention—

1. A key socket having a switch block and a spindle to which the switch block is fix-

edly secured, with an insulating body, bearings for the switch block spindle, and a key handle having a lost motion connection with the switch block spindle and bearings for the key handle.

2. A key socket having an insulating body and a spindle carrying a switch block and a cam block and contacts for the switch block with a spring to act upon the cam block and a key handle having a lost motion connection with the cam block on the spindle.

3. A key socket having an insulating body, a switch block and a cam block mounted to turn together, contacts for the switch block and a spring to act on the cam block,

and a key handle having a lost motion connection with said spindle.

4. A key socket having an insulating body, a switch block and cam block, contacts for the switch block, a spring to act upon the cam block and a key handle with a lost motion connection between the moving parts.

In testimony whereof I have signed my name to this specification, in the presence of two subscribing witnesses.

LEGER J. CASTONGUAY.
